UNITED STATES PATENT OFFICE.

JULIUS PEGEL, OF PHILADELPHIA, PENNSYLVANIA, ASSIGNOR TO PENNSYLVANIA AXMINSTER CARPET CORPORATION, OF PHILADELPHIA, PENNSYLVANIA, A CORPORATION OF NEW YORK.

DESIGN FOR A RUG.

Application filed October 18, 1927. Serial No. 23,781. Term of patent 3½ years.

To all whom it may concern:

Be it known that I, JULIUS PEGEL, a citizen of the United States, and a resident of Philadelphia, county of Philadelphia, State of Pennsylvania, have invented a new, original, and ornamental Design for Rugs, of which the following is a specification, reference being had to the accompanying drawing, forming a part thereof.

The figure represents a rug embodying the design of the present invention, a portion of the border being incomplete because of repetition of the design shown. The border as shown is continued throughout the extent thereof.

I claim:

The ornamental design for a rug substantially as shown and described.

JULIUS PEGEL.
